UNITED STATES PATENT OFFICE.

MURT L. O'NEIL, OF WARLAND, MONTANA.

BIN.

Application filed June 4, 1924. Serial No. 717,708.

To all whom it may concern:

Be it known that I, MURT L. O'NEIL, a citizen of the United States, residing at Warland, in the county of Lincoln and State 5 of Montana, have invented certain new and useful Improvements in Bins, of which the following is a full, clear, and exact description.

In building gravel roads it is of paramount importance that the gravel, crushed stone or the like, which is to be spread on the road be maintained in a uniform mixture until ready for use. For instance, where gravel or the like is discharged from 10 a chute into a large bin the larger pebbles or coarser stones will roll downward to the sides of the bin while the finer material will cling together in a pyramid. Consequently when the material is hauled to the road being constructed certain loads will contain 15 practically all fine material, while others consist almost entirely of the larger size stone, so that the theoretically uniform mixture actually consists of a patch of coarse 20 and a patch of fine.

It is an object of the present invention, therefore, to provide a bin in which the gravel or crushed stone may be deposited and stored without piling the same in a 25 single huge pyramid. To this end the invention consists of a compartment bin so designed that while all the material will be fed into a single compartment it will automatically flow over into the other compartments thereby avoiding the separation of the 30 uniform mixture into several distinct grades.

In the drawings:

Figure 1 is a plan view of one form of the invention.

Figure 2 is a vertical section taken on line 40 2-2 of Figure 1, and

Figure 3 is a vertical section taken on line 3-3 of Figure 1.

Referring to the drawings more in detail 45 the numeral 1 indicates a bin of suitable size for the storage of gravel, crushed stone or the like, and while shown as rectangular it may be of any other shape desired which is suitable to the purpose.

In the particular embodiment shown, four 50 vertical partitions designated 2, 3, 4 and 5 are diagonally arranged within the bin so as to provide a central compartment and four side compartments designated respectively 6,

7, 8, 9 and 10. The bottom of the bin is 55 formed of four downwardly and inwardly inclined walls 11 which terminate in the discharge opening 12 which is normally closed by means of the closure 13.

The partition 2 is provided with a transverse notch or recess in its upper edge as indicated by the numeral 14, and likewise the partitions 3, 4 and 5 are provided with a transversely extending openings 15, 16 and 17 respectively. By an inspection of Figures 2 and 3 it will be observed however that these openings are not at uniform distances from the top of the receptacle in the embodiment shown, but on the contrary are arranged at progressively greater distances 70 from the top.

As a consequence of the construction so far described it will be apparent that the uniformly mixed gravel or crushed stone which is fed into the central compartment 75 6 will form into a pile until it reaches the lowest opening, namely, that indicated by numeral 17. The material will then overflow through opening 17 until compartment 10 is filled. Obviously, then the material 80 will pile up in compartment 6 until the next higher opening 16 is reached when it will overflow into compartment 9, and so on until all compartments are filled. By this means 85 it is apparent that a large pyramid of the material is avoided thus preventing the gravel from separating itself into different grades.

In order to guide and direct the material 90 into the several side compartments as well as to avoid undue agitation thereof, I have provided what may be termed aprons 18 which are secured to the lower edges of the various openings and extend into the side compartments.

From the foregoing description taken in connection with the accompanying drawings it will be seen that I have devised an exceedingly simple arrangement for storing 100 gravel and the like and one in which the uniformity of the mixture stored will be maintained.

In accordance with the patent statutes I have described what I now believe to be the best embodiment of the invention, but I do not wish to be understood thereby as limiting myself or the scope of the invention, as many changes and modifications may be 105

made without departing from the spirit of the invention; all such I aim to include in the scope of the appended claims.

What I claim as new and desire to secure 5 by Letters Patent is:

1. A bin including a receptacle, a horizontal series of vertically-extending partitions in said receptacle, all of said partitions being formed with openings spaced below the 10 top of the receptacle.
2. A bin including a receptacle, a horizontal series of vertically-extending partitions in said receptacle, said partitions being formed with transversely extending openings 15 arranged at varying distances from the top of the receptacle.
3. A bin including a receptacle, a plurality of partitions in said receptacle, said partitions being formed with transversely extending openings arranged at varying distances from the top of the receptacle, and downwardly and outwardly inclined aprons 20 secured to the lower edge of each of said openings.
- 25 4. A bin including a receptacle, a horizontal series of vertical partitions arranged

diagonally of said receptacle so as to provide a central compartment and a plurality of side compartments, said partitions being formed with transversely extending openings arranged at varying distances from the 30 top of the receptacle.

5. A bin including a receptacle formed with a downwardly tapered bottom terminating in a discharge opening, a horizontal 35 series of vertical partitions arranged diagonally of said receptacle so as to provide a central compartment and a plurality of side compartments, said partitions being formed with transversely extending openings 40 arranged at varying distances from the top of the receptacle.

6. A bin including a receptacle formed with a downwardly tapered bottom terminating in a discharge opening, a plurality of 45 vertical partitions arranged in said receptacle, said partitions being formed with openings spaced below the top of said receptacle, and downwardly inclined aprons 50 secured to the lower edge of each of said openings.

MURT L. O'NEILL.
